UNITED STATES PATENT OFFICE.

SYDNEY T. FARRELL, OF BOSTON, MASSACHUSETTS.

WRENCH.

1,203,513.

Specification of Letters Patent. Patented Oct. 31, 1916.

Application filed March 14, 1916. Serial No. 84,127.

To all whom it may concern:

Be it known that I, SYDNEY T. FARRELL, a citizen of the United States, residing at Boston, in the county of Suffolk and State 5 of Massachusetts, have invented new and useful Improvements in Wrenches, of which the following is a specification.

This invention relates to wrenches and has for its primary object the provision of 10 a tool of this character which will include means for maximizing the gripping action of the clamping jaws against the object when turning the wrench in one direction and for slightly lessening the pressure 15 against one of the jaws when turning the wrench in an opposite direction. This arrangement of parts is preferred particularly when the wrench is used upon pipes, tubing or the like and it is desired to obtain 20 ratchet-like gripping action of the jaws against the pipe during the turning operation.

Another object of the invention resides in the provision of a wrench including a relatively fixed jaw and a sliding jaw, the latter being designed and associated with the shank of the structure to permit said sliding jaw to be adjusted with ease and facility as the occasion demands.

With the above and other objects in view which will appear as the nature of the invention is better understood, the same consists in the improved construction and novel arrangements of parts which will herein 35 after be fully described and particularly pointed out in the claims.

In the accompanying drawings has been illustrated a single and preferred form of the invention, it being, however, understood 40 that no limitation is necessarily made to the precise structural details therein exhibited, but that changes, alterations and modifications within the scope of the claims may be resorted to when desired.

45 In the drawings:—Figure 1 is a side view of the wrench. Fig. 2 is an edge view thereof. Fig. 3 is a section on the line 3—3 of Fig. 2. Fig. 4 is a section on the line 4—4 of Fig. 3.

50 The wrench consists of a shank 1, of substantially U shaped formation as illustrated in Fig. 4, providing a central channel 2, which extends throughout the entire length of the shank along one side thereof. This

shank is secured in any suitable well known 55 manner to a handle 3. At the opposite end the channel 2 is extended for the entire width of the shank as at 4, to permit the tilting jaw 5 to be projected operatively therethrough. The said tilting jaw is provided with a continuous shank 6, which is freely movable in the channel 2. A pivot pin 7 extends through the main fixed shank 1, and through the jaw 5, as clearly shown 65 in Figs. 1 and 2.

The sliding jaw 8, is provided with a yoke 9, which freely receives the shank 1, and this yoke also receives the tilting shank 6 therein as clearly shown in Fig. 4. A leaf spring 10 is secured at 11, to the yoke portion of the sliding jaw 8, the said spring having a relatively free terminal 12, which bears against the shank 6. In this manner, it will be observed that by simply pressing the sliding jaw 8, along its surface 13, the 75 teeth 14 will be moved relatively to the co-acting teeth 15, formed along one edge of the mentioned shank 1. Ordinarily, the teeth 14 are held actively engaged with the teeth 15 under the action of the spring 10. 80 It will be fully understood that when pressure is applied to the sliding jaw to separate the teeth 14 from the teeth 15, said jaw may be moved to the requisite point relatively to the mating jaw 5, and on releasing 85 such pressure, the sliding jaw will be automatically brought into co-acting contact with the teeth 15.

When pressure is applied to the handle 3, in the direction of the arrow (a), the companion jaws 5 and 8 will be brought into maximum gripping engagement with the object between said jaws, while when pressure is applied to the handle 3 to move the same in the direction of the arrow (b), the 95 tilting jaw 5 will move to a slight extent relatively of the sliding jaw and as a consequence thereof, the wrench may be quickly operated in substantially ratchet-like manner and a new purchase of the mating jaws 100 against the pipe effected in quick succession. This arrangement is preferred when working upon pipes, tubing or like bodies.

I claim:—

1. A wrench comprising, a fixed shank 105 having a tilting jaw, a sliding jaw on the shank, means on the sliding jaw, and means on the shank, the latter co-acting with the

first means to hold the sliding jaw against movement in one direction upon said shank, the shank having a channel therein, and an integral portion formed on the tilting jaw and extending into said channel.

2. A wrench comprising, a fixed shank having a tilting jaw, a sliding jaw on the shank, means on the sliding jaw, and means on the shank, the latter co-acting with the

10 first means to hold the sliding jaw against movement in one direction upon said shank, the shank having a channel therein, an integral portion formed on the tilting jaw and extending into said channel, and a

15 spring carried by the sliding jaw and bearing against said integral portion and operating to hold the means of said sliding jaw

in normal engagement with the means of said shank.

3. A wrench comprising a shank having a channel along one side, a tilting jaw having a portion extending into said channel and contacting with the walls thereof, a sliding jaw, means for supporting the sliding jaw for movement laterally of the shank, and mechanism for holding the sliding jaw against sliding movement in one direction. 20 25

In testimony whereof I, affix my signature in presence of two witnesses.

SYDNEY T. FARRELL.
